Albert R. Forgue, Waterbury, Conn., assignor to Alan Products, Inc.

Filed Oct. 8, 1962, Ser. No. 72,025

Term of patent 14 years

(Cl. D86—10)

FIG. 1

FIG. 2

FIG. 3

FIG. 4

FIG. 1 is a side elevation of a combined cosmetic smoother and cap therefor, showing my new design.

FIG. 2 is a side elevation thereof, showing the cap member in separated position.

FIG. 3 is a front elevation of the applicator member with the cap member omitted for convenience of illustration.

FIG. 4 is a bottom plan view thereof, as shown in FIG. 3.

The undisclosed side of the applicator member is substantially plain and unornamented and is arcuately curved as shown in FIG. 2.

I claim:

The ornamental design for a combined cosmetic smoother and cap therefor, as shown and described.
